[57] CLAIM

The ornamental design for a whirlpool jet nozzle for bathtubs or the like, substantially as shown and described.

DESCRIPTION

FIG. 1 is a front, left side perspective view of a whirlpool jet nozzle for bathtubs or the like, showing my new design;

FIG. 2 is a side elevational view thereof, the opposite side being identical thereto;

FIG. 3 is a front elevational view thereof;

FIG. 4 is a rear elevational view thereof;

FIG. 5 is a top plan view thereof;

FIG. 6 is a bottom plan view thereof;

FIG. 7 is a cross-sectional view thereof, taken along line 7—7 of FIG. 1.

FIG. 1

FIG. 2

FIG. 3

FIG. 4

FIG. 5
